WING ASSEMBLY FOR WALLETS, PASS CASES AND THE LIKE

Benjamin B. Osher, Laurence, N. Y., assignor to American Kleer-Vu Plastics, Inc., Maspeth, N. Y.

Application April 12, 1956, Serial No. 577,805

4 Claims. (Cl. 150—39)

This invention relates to a wallet, pass case or the like, and more particularly to a wing assembly for a wallet or pass case.

The object of the invention is to provide a wing assembly which can be readily attached to a wallet, pass case or the like whereby a plurality of cards, photographs, or other material can be conveniently carried.

A further object of the invention is to provide a wing assembly for use with a wallet, pass case or the like, the wing assembly of the present invention including a body member which has transparent holders or support members secured thereto, the wing assembly adapted to be secured to a suitable backing member in any suitable manner, as for example by means of a bracket, or bar whereby the bar may either be of the one piece type or two piece type, or else the body member can be secured in place by means of an adhesive or by a suitable line of stitching.

A further object of the invention is to provide a wing assembly for use with a wallet, pass case or the like, the wing assembly being constructed so that it will be rigidly held in place so that a plurality of cards or photographs can be carried in a wallet or the like, the wing assembly including a means for permitting the device to be readily detached when desired and whereby additional wing assemblies can be mounted in place whenever desired or required.

A further object of the invention is to provide a wing assembly which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a plan view of a wing assembly, constructed according to the present invention.

Figure 2 is a sectional view taken on the line 2—2 of Figure 1.

Figure 3 is a sectional view taken on the line 3—3 of Figure 1.

Figure 4 is a fragmentary enlarged side elevational view of a bracket, with parts broken away and in section.

Figure 5 is an end elevational view illustrating the present invention arranged in a wallet or pass case.

Figure 6 is a fragmentary sectional view illustrating a modification wherein the body member is secured by stitching to the backing member.

Figure 7 is a view similar to Figure 2, but showing a modified bracket.

Figure 8 is a fragmentary plan view of a further modified wing assembly.

Figure 9 is a view similar to Figure 8 but showing a further modified wing assembly.

Referring in detail to the drawings, the numeral 10 designates a body member which can be made of any suitable material such as plastic, cardboard, leather or the like, and secured to the body member 10 is a pair of

2

transparent support members 11 which are made of a suitable material such as an acetate type of plastic. Each of the support members 11 may have the same construction and each includes a pair of superposed walls 12 and 13 which may be interconnected together along one longitudinal edge. One of the walls such as the walls 13 may terminate in a flap 14 which is arranged in over-lapping relation with respect to the other wall 12. Ends of the support members 11 may be provided with recesses 15 whereby a person's fingers can be readily arranged in engagement with cards, photographs or the like which are interposed between the pair of walls 12 and 13.

Each end of the body member 10 is provided with a cutout which is indicated generally by the numeral 16, and the cutout 16 includes a straight portion 17 which terminates in an inner arcuate or circular portion 18. The outer end of each of the straight portions 17 terminates in a wide or flaring portion 19.

There is further provided a bracket 20 which can be used for securing a plurality of the wing assemblies together or else the bracket can be used for securing the wing assemblies to a wallet, backing member or the like. The bracket 20 may be made of any suitable material such as metal and includes a first section 21 which terminates in a right angularly arranged second section 22, and extending transversely from the second section 22 is a third section 23. The third section 23 is provided with an offset portion 24, and the outer end of the section 23 terminates in a reduced diameter trunnion 25. The trunnion 25 is releasably mounted in an aperture or opening 26 in a fourth section 27 which extends from an end of the first section 21. The outer end of the section 27 is curved as at 28. Thus, by applying finger pressure to the offset portion 24 of the section 23, the bracket 20 can be released as when the various wing assemblies are to be removed or replaced.

Referring to Figure 5 of the drawings, there is illustrated a wallet, pass case or the like which is indicated generally by the numeral 29, while the numeral 30 designates a backing member. The wallet 29 may be provided with pockets 31 which receive end portions of the backing member 30, and the bracket 20 may be connected to the backing member 30, for supporting a plurality of the wing assemblies.

As shown in Figure 1, each of the walls 12 and 13 of the support members 11 terminates in an inner flange 32 of rectangular shape, and the flanges 32 are secured in any suitable manner, as by means of an adhesive, to the outer surface of the body member 10.

Referring to Figure 6 of the drawings, there is shown a modified arrangement wherein the numeral 33 designates a backing member which may have a body member 34 secured thereto as by means of stitching 35. The body member 34 may have the pair of support members 11 extending therefrom.

Referring to Figure 7 of the drawings, there is shown a modified bracket which is indicated generally by the numeral 36, and the bracket 36 may consist of two pieces. One of the pieces includes a first portion 37 which has second portions 38 extending outwardly from each end thereof. There is further provided a rod 39 which has reduced diameter trunnions 40 on each end thereof for engagement with apertures or openings in the portions 38. The portions 38 may extend through cutouts in the body member.

Referring to Figure 8 of the drawings, there is shown a modified wing assembly which is indicated generally by the numeral 41, and the wing assembly 41 includes a body member 42 which has support members 11 secured thereto. The body member 42 may have a cutout 43 in each end, and each cutout 43 includes a flaring

portion 44 which terminates in an inner enlarged circular portion 45.

In Figure 9 there is shown a still further modified wing assembly which is indicated generally by the numeral 46. The wing assembly 46 includes a body member 47 which has a pair of support members 11 secured thereto. There is provided on each end of the body member 47 a cutout 50, and each cutout 50 includes a substantially rectangular shape portion 48 and a wide portion 49 having rounded edges adjacent thereto.

From the foregoing, it is apparent that there has been provided a wing assembly which is especially suitable for use in wallets, pass cases or the like. In use, cards, photographs or other members or articles can be inserted in the transparent support members 11. Thus, due to the provision of the flaps 14, the walls 12 and 13 can be expanded sufficiently to permit the insertion of cards or other articles into the support members and the cards or articles will be retained in their proper position in the support members. A plurality of the wing assemblies can be mounted on a single bracket such as the bracket 20 or the bracket 36. Thus, as shown in Figure 2 the portions 27 and 22 of the bracket 20 extend through the circular portions 18 of the cutouts 16 so that with the parts of the bracket in the position shown in Figure 2, a plurality of the body members 10 will be maintained connected together. Thus, a plurality of different articles can be supported in a wallet, pass case or the like. When it is desired to remove or replace articles from any of the support members 11, such articles can be readily removed by means of the finger recesses 15 and due to the provision of the overlapping flap 14 which permits flexing of the walls 12 and 13 relative to each other. Also, by disengaging the trunnion 25 from the aperture 26, the bracket 20 can be disengaged or released so that the number of body members 10 or wing assemblies can be varied as desired. The inherent resiliency of the parts of the bracket 20 serve to maintain the parts in their proper assembled position. The support members 11 include the flanges 32 which are secured to the body member 10 in any suitable manner, as for example by means of an adhesive. As shown in Figure 5 the bracket 20 may be connected to a backing member 30, and end portions of the backing member 30 may engage pockets 31 which form part of a wallet 29. Thus, a hinged arrangement is provided whereby the various support members 11 can be swung or pivoted about an axis extending through the bracket 20 so that access can be had to any of the articles in the support members. In Figure 6 there is shown a modification wherein instead of using a bracket such as the bracket 20, a body member 34 is secured to a backing member 33 by means of a suitable line of stitching 35. In Figure 7 there is shown a modified bracket which is indicated by the numeral 36, and the bracket 36 may be a two piece type which includes the removable rod 39. Thus, due to the provisions of the cutouts such as the cutout 16 in each end of the body member 10, the wing assembly can be used with either a one piece bracket as shown in Figure 2 or a two piece bracket as shown in Figure 7. In Figure 8 there is shown a modified wing assembly which includes a body member 42 having cutouts 43 in each end. In Figure 9 there is shown a further modified wing assembly 46 which includes a body member 47 having a different shaped cutout 50 in each end. The wing assemblies shown in Figures 8 and 9 are adapted to be used with either of the brackets 20 or 36 shown in Figures 2 and 7.

With the present invention, the wing assembly can be used with brackets having different types of prongs such as the one piece bracket 20 or the two piece bracket

36. Or, as shown in Figure 6 the body member 34 can be sewn in place to a backing member. The cutouts may be of different shapes as shown in Figures 1, 8 and 9. The cutouts insure that the wing assemblies can be readily inserted and the cutouts insure that the parts will not accidentally work loose from their proper position.

I claim:

1. In a wing assembly, a body member having a cutout in each end thereof, each of said cutouts including 10 a straight portion terminating in an enlarged circular portion, the outer end of each straight portion terminating in a flaring portion, a pair of transparent support members extending outwardly from the longitudinal side portions of said body member and secured thereto, each of 15 said support members including superposed first and second walls having a longitudinal edge connected together, a flap extending from one of said walls and overlapping the other wall, the outer ends of said support members being provided with finger engaging recesses, 20 the inner end of each of said walls terminating in a rectangular flange, said flanges being secured to the outer surface of said body member.
2. A wing assembly comprising a body member having a cutout in each end thereof, each of said cutouts including 25 a flaring portion terminating in an inner enlarged circular portion, a pair of transparent support members extending outwardly from the longitudinal side portions of said body member and secured thereto, each of said body members including superposed first and second walls 30 having a longitudinal edge connected together, a flap extending from one of said walls and overlapping the other wall, the inner end of each of said walls terminating in a rectangular flange, said flanges being secured to the outer surface of said body member.
3. In a wing assembly, a body member having a cutout in each end thereof, each of said cutouts including a substantially rectangular portion terminating in an outer flaring portion, a pair of transparent support members extending outwardly from the longitudinal side portions 40 of said body member and secured thereto, each of said body members including superposed first and second walls having a longitudinal edge connected together, a flap extending from one of said walls and overlapping the other wall, the inner end of each of said walls terminating 45 in a rectangular flange, said flanges being secured to the outer surface of said body member.
4. A wing assembly, comprising a body member having a cut-out extending inwardly from each end thereof, said cut-outs terminating in outer flaring portions, a pair of 50 transparent support members extending outwardly from the longitudinal side portions of said body member and secured thereto, each of said support members including superposed first and second walls having a longitudinal edge connected together, a flap extending from one of 55 said walls and overlapping the other wall, the outer ends of said support members being provided with finger engaging recesses, the inner end of each of said walls terminating in a rectangular flange, said flanges being secured to the outer surface of said body member.
